CLAIM

The ornamental design for an earplug, as shown and described.

DESCRIPTION

FIG. 1 is a left, front-perspective view of an earplug;
 FIG. 2 is a right, rear-perspective view of the earplug;
 FIG. 3 is a right, side-view of the earplug, the left, side-view
 being a mirror image thereof;
 FIG. 4 is a rear-view of the earplug; and,
 FIG. 5 is a front-view of the earplug.
